VERTICALLY FLUED RICH GAS FIRED COKE
OVEN BATTERYFrans Wethly, Manhasset, N. Y., assignor to
Allied Chemical & Dye Corporation, New York,
N. Y., a corporation of New York

Application August 4, 1948, Serial No. 42,425

5 Claims. (Cl. 202—144)

1

This invention relates to a rich gas fired, vertically flued coke oven battery of great strength and durability and therefore adapted to coke all coking coals including coals of low volatile content, e. g., containing less than about 26% of volatile matter. Such low volatile coals exert pressures in excess of 2 pounds per square inch when coked and therefore cannot be coked in the heretofore known types of coke oven batteries in general use.

In my copending application Serial No. 585,236 filed March 28, 1945, which issued as Patent No. 2,460,324 on February 1, 1949, I have disclosed and claimed a combination vertically flued coke oven battery adapted to coke low volatile coals. The present application is directed to a novel rich gas fired, vertically flued coke oven battery for coking low volatile and other coking coals.

It is an object of this invention to provide a regenerative, vertically flued rich gas fired coke oven battery of great strength and durability and therefore adapted to coke all coking coals including low volatile coals, which battery is unusually simple and compact in design and efficient in operation.

Other objects and advantages of this invention will be apparent from the following detailed description thereof.

The rich gas fired coke oven battery of this invention comprises in combination a plurality of horizontally-elongated cell-defining walls disposed in spaced relation to define horizontally-elongated cells. A horizontally-elongated coking chamber is disposed in the upper portion of each cell. Beneath this coking chamber in the lower portion of each cell is disposed a row of inflow and outflow regenerators. Each cell-defining wall comprises a heat-transmitting wall at each side thereof, each such heat-transmitting wall defining a side wall of the coking chamber contiguous thereto. In addition the cell-defining wall comprises two rows of vertical flues, one row on one side and the other row on the other side of the upper portion of the cell-defining wall, and a massive refractory wall extending crosswise of the battery between the two rows of vertical flues, this massive wall being devoid of openings, extending from top to bottom of the cell-defining wall and of a thickness at least four times the thickness of the heat-transmitting wall. This massive wall provides a gas-tight barrier separating a coking chamber, the row of vertical flues for heating one side of this coking chamber and the row of regenerators therebeneath on one side of this

2

massive wall from the coking chamber, the row of vertical flues for heating one side of this chamber and the row of regenerators therebeneath on the other side of this massive wall. It also buttresses the heating flues so that the heat-transmitting walls are capable of withstanding, without substantial deformation or spalling, the pressures generated in the coking of low volatile coals. Moreover, this construction results in the

5 supplying of preheated air and gas to the heating flues of each coking chamber and the withdrawal of products of combustion from these heating flues independently of the supply of these media to and the withdrawal of products of combustion from the flues associated with adjacent coking chambers, permitting regulation of the heating of each coking chamber of the battery independently of the others to obtain optimum coking.

10 In the preferred embodiment illustrated on the drawings the invention is shown incorporated in a rich gas fired underjet oven battery and the description which follows will be confined to the present illustrated embodiment of the invention. It will be understood, however,

15 the novel features and improvements are not limited to this embodiment of the invention, but the invention includes coke oven batteries in which the rich gas, e. g., coke oven gas, is supplied to the flues from conduits disposed in the oven brickwork in the vicinity above the regenerators and beneath the base of the coking chambers, i. e., ovens of the gas gun type. Hence, the scope of this invention is not confined to the embodiment herein described.

20 In the accompanying drawings forming a part of this specification and showing for purposes of exemplification a preferred embodiment of the invention but without limiting the claimed invention to this embodiment:

25 Figure 1 is a composite vertical section taken crosswise of the battery, the left-hand portion being taken through a heating wall, which in the interests of clarity is shown in full lines and the right-hand portion being taken through a coking chamber, of a coke oven battery embodying the present invention; and

30 Figure 2 is a fragmentary vertical section taken lengthwise of the battery in a plane passing through line 2—2 of Figure 1.

35 Referring to the drawings, the coke oven battery comprises a deck or oven base 10 which extends the full length and width of the battery and supports the battery brickwork. The deck 10 is ordinarily formed of reinforced concrete and may be a single slab, although preferably it

is divided into a plurality of longitudinal sections separated by expansion joints, as is well known. This deck 10 is supported by a multiplicity of columns 11 which may be of reinforced concrete. These columns are disposed longitudinally of the battery and also crosswise of the battery. Concrete walls 12 and 13 are disposed at the sides of the battery producing with the deck an enclosed basement space 14. Conventional pinion walls 15 (Figure 2) are provided at the ends of the battery for additionally supporting deck member 10 and for retaining in place the brick-work hereinafter described supported on the deck member 10.

Disposed at spaced points along the length of deck 10 and extending crosswise of the battery are parallel cell-defining walls 16 (Figure 2). These walls 16 define the side walls of horizontally-elongated cells 17 in side by side relationship; the distance between the median of one cell and the median of a contiguous cell preferably is from 4½ to 5 feet.

Each cell-defining wall 16 comprises (1) a heat-transmitting wall 18 on opposite sides thereof, (2) two rows 19 and 20 of vertical flues, and (3) a massive refractory wall 21 extending crosswise of the battery between the two rows 19 and 20 of vertical flues. Massive wall 21 extends the full height of the cell-defining wall, is devoid of openings and of a thickness at least four times the thickness of the heat-transmitting wall 18. Each heat-transmitting wall 18 desirably is of silica brick shapes and of a thickness from 3 to 4½ inches, preferably 3¾" thick. Each massive wall 21 consists of an interior portion 22 constituted of machine made, relatively inexpensive silica brick known as "straights," desirably from 9½" to 18½", preferably about 13½" thick, and a liner 23 on each side of the interior portion 22, which liner with the heat-transmitting wall 18 and the intersecting walls 24 (Figure 1) forms the vertical flues. Liner 23 and walls 24, as customary, are made from silica brick shapes to produce flues of desired configuration. Liner 23 may have a thickness of from 2½" to 5". Thus, the combined thickness of the interior portion 22 and the liners 23 of each massive wall 21 separating the two groups of flues 19 and 20 is from 14½" to 28½", preferably about 17½".

In the upper portion of each cell 17 is a horizontally-elongated coking chamber 25. Each coking chamber in horizontal cross-section is of tapered shape, as is conventional, the wide end of the coking chamber being on the coke side of the battery, i. e., the side at which the coke is discharged from the coking chambers, and the narrower end on the pusher side. Disposed directly beneath this coking chamber 25 in each cell 17 is a row of regenerators 26, each containing conventional heat storing refractory material such as checker brick. Each row of regenerators is constituted of two exterior regenerators 27, one of which is shown in Figure 1, and an interior regenerator 28. Each row of regenerators is provided at its base with a pair of sole channels or passages 29 and 29' extending from one side of the battery; air is supplied to and products of combustion withdrawn from the bottom of the regenerators through the sole channels 29 and 29'. Sole channel 29 communicates only with the exterior regenerators 27 and sole channel 29' communicates only with the interior regenerator 28.

A chimney flue 30 is located on one side of the

battery and runs the full length thereof. This chimney flue may be disposed on the coke or pusher side of the battery. In the embodiment shown on the drawing, it is positioned on the coke side of the battery. Located at the same side of the battery as the chimney flue are reversing valves 31 which may take various forms and which collectively provide for the discharge of the products of combustion from the regenerators through the sole channels 29, 29' into chimney flue 30 and for the supply of air to the regenerators. Air is supplied to the inflow regenerators through passageways 32 communicably connecting the basement space 14 with the sole channels 29, 29'. In the structure shown on Figure 1 a valve 33 controls the flow of air from the basement space 14 through the passageway 32 into a sole channel 29 or 29' of the inflow regenerators of each row. This valve is shown in open position in Figure 1. A valve 34 is provided for controlling the flow of products of combustion from each sole channel 29, 29' of the outflow regenerators into the chimney flue 30. A butterfly valve 35 is positioned in a passageway 36 connecting each sole channel 29, 29' with the chimney flue 30, which butterfly valve may be suitably positioned by the operator to obtain the desired stack draft, causing flow of the products of combustion into the chimney flue 30.

It will be understood valves similar to 33 and 34 are provided for the sole channels communicating with each of the regenerators of each row of regenerators, which valves control the flow of air into the inflow regenerators from the basement space 14 and the flow of products of combustion from the outflow regenerators into the chimney flue 30. Thus, when the valves 33 controlling the flow of air into the interior regenerators 28 along the length of the battery are closed, the corresponding valves controlling the flow of air into the exterior regenerators 27 are open. Likewise, when the valves 34 controlling the flow of products of combustion from the interior regenerators 28 along the length of the battery into the chimney flue 30 are open, the corresponding valves 34 in the passageways connecting the sole channels 29 of the exterior regenerators 27 with the chimney flue 30 are closed. Each passageway connecting the basement space with the sole channel may be provided with a port 37 which may be throttled by removable and replaceable finger bars.

Each coking chamber 25 is preferably provided with a plurality of charging holes 38 and with the usual valve controlled gas offtake 39 communicating with the collector main system. The ends of the coking chambers, as conventional, are adapted to be closed by removable doors of any well known type.

Each row of heating flues 19 and 20 are communicably connected with other flues of the same row but not with the flues of other rows. Each row of flues involves on the pusher side of the battery a concurrently operable group of vertical flues 40 to 47, inclusive, communicating at their tops through a horizontal flue 48 with a group of flues 49 to 56, inclusive. On the coke side of the battery an exterior group of vertical flues 57 to 62, inclusive, is connected by horizontal flue 63 to the interior groups of flues 64 to 70, inclusive. Thus, in the embodiment of the invention shown on the drawings each cell-defining wall involves two rows of vertical flues, each row of flues is constituted of two outer and two inner groups of

flues, the outer groups operating concurrently for inflow, while the inner groups operate concurrently for outflow. Upon reversal the inner groups of flues of each row operate as inflow flues, while the outer groups operate concurrently as outflow flues.

Flow through each flue may be controlled by a slide brick or damper brick 71 to vary the extent of the passage connecting the vertical flues with the horizontal flues 48 and 63. Each slide brick may be advanced more or less over the passage connecting the vertical flue with the horizontal flue through access flue 72, which extends from the horizontal flues to the top of the battery. The base of each flue is provided with a burner for supplying rich fuel gas, such as coke oven gas, thereto. Crosswise of the battery the flues are provided alternately with low burners 73 and high burners 14.

Each flue receives rich gas, such as coke oven gas or other rich fuel gas, through an individual uprising channel 75 extending through deck 10 and connected at its lower end with one of a pair of gas distributing mains 76 disposed in the basement space 14 near the top thereof crosswise of the battery. These crosswise extending mains 76 are provided with individual uprising channels 77, one of the mains 76 being provided with such channels communicating only with the exterior groups of flues in the heating wall thereabove and the other main with such channels communicating only with the interior groups of flues in the heating wall thereabove. Each uprising channel 77 at the point where it is connected with main 76 is provided with a flow regulator (not shown) controlling the flow of gas supplied to the flue. This flow regulator preferably is of the type described and claimed in Patent 2,199,961 of May 7, 1940. These regulating devices require attention and occasional adjustment by an attendant working in basement space 14.

Each main 76 communicates with a rich gas supply main 78 connected therewith by means of piping 79. Main 78 is suitably insulated against loss of heat. Piping 79 is provided with a three-way valve 80 and a shutoff valve 81 which is normally open. Leading into the three-way valve 80 is a pipe 82 which communicates with a decarbonizing air main 83 suitably supported in the basement space 14. Operation of the three-way valve 80 by the usual automatic reversal mechanism functions to place the main 78 into communication with the mains 76 serving to supply coke oven gas to the inflow flues and to place the decarbonizing air main 83 into communication with the mains 76 to which coke oven gas is not being supplied. Upon reversal of operation the three-way valve is operated to place decarbonizing air main in communication with the cross mains 76 to which previously fuel gas had been supplied in accordance with customary procedure of supplying fuel gas and decarbonizing air to the gas distribution systems of coke oven batteries.

The exterior regenerators 27 of each row of regenerators in each cell 17, as shown in Figure 2, are connected by ports 84 and 85 with the outer groups of flues on opposite sides of the coking chamber thereabove. The inner regenerator 28 of each row of regenerators is connected by like ports with the inner groups of flues on opposite sides of the coking chamber directly above it.

All of the exterior regenerators 27 of each row of regenerators during one period of operation

of the battery operate for inflow of preheated air into the communicably connected outer groups of flues 40 to 41 and 57 to 62, both inclusive, located on opposite sides of the coking chamber thereabove, while the products of combustion pass downwardly through the inner groups of flues 49 to 56 and 64 to 70 on opposite sides of the coking chamber into the inner regenerator 28. Upon reversal inner regenerator 28 of each row of regenerators and the flues communicating therewith operate for inflow while products of combustion pass downwardly through the outer groups of flues and the outer regenerators 27. Thus, all of the regenerators in alignment longitudinally of the battery operate simultaneously for flow in the same direction.

It will be understood that, if desired, a pair of inner regenerators may be used instead of each regenerator 28, one individual to the two groups of flues 64 to 70 on opposite sides of a coking chamber and the other individual to the two groups of flues 49 to 56 on opposite sides of the coking chamber. Also a relatively thin crosswise extending partition may be disposed along the median plane of the regenerators shown in the drawings to divide each regenerator into two equal compartments so that each row of flues communicates with a separate row of regenerators.

Located at the other side of the battery is an air channel or passageway 87 running the full length of the battery to which air may be supplied through one or both ends thereof. If desired, a fan or blower (not shown) may be disposed at one end of the air channel 87 with its outlet arranged to blow the air at any desired pressure, say at about a 5 mm. water gauge above atmospheric, into the channel 87. The air admitted to the channel may be passed through a filter cloth or other screen so that clean air of predetermined humidity is admitted to the channel and flows through openings 88 into the basement space 14 and from this space into the regenerators. Operating in this manner air of constant oxygen content is admitted to the regenerators throughout the year minimizing the necessity of changing adjustments of the regulating devices with seasonal changes in atmospheric conditions. Furthermore, comfortable conditions for the attendant are maintained in the basement space 14 at all times.

Benches 89 and 90 are provided on opposite sides of the coke oven battery on which benches travel the machinery, such as the coke oven door, pusher and coke-guide handling machines usually associated with a coke oven battery.

It will be noted that in the coke oven battery of this invention the upper portions of the cell-defining walls are in effect heating walls of greatly increased strength, buttressing the vertical heating flue and minimizing spalling and deformation of the heat-transmitting walls. Hence, low volatile and other coking coals which generate high pressure, for example, coal charges containing as low as 18% volatiles, which may develop pressures as high as 10 pounds per square inch, may be coked in the battery of this invention. Further in the regenerator and vertical flue arrangement of the battery of this invention, the flow of preheated air and fuel gas to and the flow of products of combustion from the flues associated with each coking chamber are independent of the flow of these media to and the flow of products of combustion from other coking chambers including the adjacent coking

chambers. This permits control of the supply of the proper amount of air and rich fuel gas to the flues of each coking chamber independently of that supplied to the other coking chambers with consequent improvement in the coking effected in each coking chamber.

The construction of the cell-defining walls permits replacement of the special brick shapes defining the heating flues, should they become worn out or defective for any reason. In prior types of batteries, should the heating flues become cracked and spalled, it was necessary to rebuild the entire battery. With the construction of this invention the massive walls 22 built from relatively inexpensive machine-made brick straights are practically indestructible and serve as supporting and strengthening walls for the liners 23 and the heat-transmitting walls 18, which therefore may be made relatively thin and replaced when necessary. For example, liners 23 may be made 2½" thick and heat-transmitting wall 18, 3¾" thick. Present standard practice is to have the heat-transmitting walls 4½" thick or thicker. The use of thinner heat-transmitting walls and the employment of massive walls 24, which serve as heat reservoirs effecting improved heating of the fresh coal charges introduced into the coking chambers, permits a substantially lower flue temperature to be maintained without affecting the coking rate, or, conversely, results in a faster coking rate with the same flue temperature with consequent material increase in capacity of the oven battery. Thus, whereas present ovens of latest design have a coking rate of 1.2" per hour with a flue temperature of 2550° F., the oven of the invention can be operated with a flue temperature of 2300° F. (250° F. lower) at the same coking rate, or operated with a flue temperature of 2550° F. in which case the coking rate is increased to 1.4" per hour, an increase in capacity of about 17%. Furthermore, should it be necessary to replace the liners 23 and heat-transmitting walls 18 of one coking chamber, this can readily be done without deformation or spalling of the silica brick-work forming the liners and heat-transmitting walls of adjacent coking chambers because, as noted above, the supply of preheated air and fuel gas to and withdrawal of products of combustion from the heating flues of each coking chamber is independent of the supply of these media to and withdrawal of combustion products from the heating flues of adjacent coking chambers. Hence, when repairs are made in the heating flues of one coking chamber, temperature conditions may readily be maintained in the heating flues of adjacent coking chambers high enough to prevent such deformation or spalling of the silica brick-work thereof.

The above factors and the greater durability of the coke oven battery of this invention results in important economies in the construction and operation of the battery; it results in a material reduction in the number of more costly special silica brick required in the construction of the battery, in a substantial reduction in the cost of maintenance and operation of the battery and greatly prolongs the effective life of the battery. Furthermore, as noted above, the invention results in a material improvement in the coking rate.

While the drawings illustrate the invention applied to a battery involving heating walls equipped with rows of flues arranged in two ex-

terior and two interior groups, it will be evident that the invention may be embodied in batteries involving other vertical flue arrangements in which the vertical flues communicate with other vertical flues of the same row, but not with flues of other rows, as, for example, the twin vertical flue arrangement disclosed in Figures 3 and 4 of my Patent No. 2,407,356 granted September 10, 1946. Further, the invention may be incorporated in batteries having two waste heat flues as disclosed in Pavitt United States Patent 2,155,954 of April 25, 1939.

Since certain changes may be made without departing from the scope of the invention, it is intended that the above description shall be interpreted as illustrative and not in a limiting sense.

What is claimed is:

1. A coke oven battery comprising, in combination, a plurality of horizontally-elongated cell-defining walls disposed in spaced relation defining horizontally-elongated cells disposed in side-by-side relation; a horizontally-elongated coking chamber in the upper portion of each cell; a row of crosswise-extending air inflow and products of combustion outflow regenerators in the lower portion of each cell directly beneath the coking chamber in said cell; each cell-defining wall comprising a heat-transmitting wall on each side thereof, two rows of vertical flues, one row being positioned on one side and the other row on the other side of the upper portion of said cell-defining wall, and a massive refractory wall extending crosswise of the battery between said two rows of flues, said massive wall extending the full height of the cell-defining wall being devoid of openings and of a thickness at least four times the thickness of said heat-transmitting wall, each row of vertical flues containing inflow and outflow flues communicating at their upper ends with flues of the same row but not with flues of other rows, the inflow and outflow flues on opposite sides of each coking chamber communicating, respectively, with the inflow and outflow regenerators disposed beneath said coking chamber and the regenerators in each cell communicating only with the heating flues on opposite sides of the coking chamber in said cell, whereby the supply of heated air to the heating flues of each coking chamber and the withdrawal of the products of combustion from these heating flues is independent of the supply of heated air to and the withdrawal of products of combustion from the flues associated with other coking chambers of the coke oven battery thus permitting regulation of the heating of each coking chamber independently of the other coking chambers of the battery.

2. A coke oven battery comprising, in combination, a plurality of cell-defining walls disposed in spaced relation defining horizontally-elongated cells disposed in side-by-side relation; a horizontally-elongated coking chamber in the upper portion of each cell; a row of crosswise-extending air inflow and products of combustion outflow regenerators in the lower portion of each cell directly beneath the coking chamber in said cell; each cell-defining wall comprising a heat-transmitting wall on each side thereof, two rows of vertical flues, one row being positioned on one side and the other row on the other side of the upper portion of said cell-defining wall, and a massive refractory wall extending crosswise of the battery between said two rows of flues, said massive wall extending the full height of the

cell-defining wall, being devoid of openings, from 14½ to 28½ inches thick and of a thickness at least four times the thickness of said heat-transmitting wall, each row of vertical flues being arranged in inflow and outflow groups of flues communicating at their upper ends with flues of the same row but not with flues of other rows, the inflow and outflow groups of flues on opposite sides of each coking chamber communicating, respectively, with the inflow and outflow regenerators disposed beneath said coking chamber and the regenerators in each cell communicating only with the heating flues on opposite sides of the coking chamber in said cell, whereby the supply of heated air to the heating flues of each coking chamber and the withdrawal of the products of combustion from these heating flues is independent of the supply of heated air to and the withdrawal of products of combustion from the flues associated with other coking chambers of the coke oven battery thus permitting regulation of the heating of each coking chamber independently of the other coking chambers of the battery.

3. A coke oven battery comprising, in combination, a mat; a basement beneath said mat; a plurality of horizontally-elongated cell-defining walls disposed on said mat in spaced relationship defining horizontally-elongated cells disposed in side-by-side relationship; a horizontally-elongated coking chamber in the upper portion of each cell; a row of crosswise-extending air inflow and products of combustion outflow regenerators in the lower portion of each cell directly beneath the coking chamber in said cell; each cell-defining wall comprising a heat-transmitting wall on each side thereof, two rows of vertical flues, one row being positioned on one side and the other row on the other side of the upper portion of said cell-defining wall, a massive refractory wall extending crosswise of the battery between said two rows of flues, said massive wall extending the full height of the cell-defining wall being devoid of openings and of a thickness at least four times the thickness of said heat-transmitting wall, each row of vertical flues containing inflow and outflow flues communicating at their upper ends with flues of the same row but not with flues of other rows, the inflow and outflow flues on opposite sides of each coking chamber communicating, respectively, with the inflow and outflow regenerators disposed beneath said coking chamber, and the regenerators in each cell communicating only with the heating flues on opposite sides of the coking chamber in said cell, whereby the supply of heated air to the heating flues of each coking chamber and the withdrawal of the products of combustion from these heating flues is independent of the supply of heated air to and the withdrawal of products of combustion from the flues associated with other coking chambers of the coke oven battery thus permitting regulation of the heating of each coking chamber independently of the other coking chambers of the battery, an air duct disposed at one side of the battery to supply air to the basement space, conduits at the other side of the battery connecting the basement space with the regenerators, a chimney flue disposed at the said other side of the battery, rich gas mains disposed in the basement space, and gas burners in said flues communicably connected with said gas mains by ducts passing through said massive refractory walls.

4. A coke oven battery comprising, in combination, a plurality of horizontally-elongated cell-

defining walls disposed in spaced relationship defining horizontally-elongated cells spaced from each other so that the median of each cell is spaced from the median of a contiguous cell a distance of from 4½ to 5 feet; a horizontally-elongated coking chamber in the upper portion of each cell; each cell-defining wall comprising a heat-transmitting wall on each side thereof defining a side wall of each of the two coking chambers on opposite sides of said cell-defining wall, two rows of vertical flues, one row being positioned at one side and the other row on the other side of the upper portion of said cell-defining wall, each row of flues comprising two exterior and two interior groups of flues, channels connecting the tops of the exterior groups, respectively, with the tops of the interior groups, the two exterior groups being simultaneously operable for flow in one direction and the two interior groups being simultaneously operable for flow in the opposite direction, and a massive refractory wall extending crosswise of the battery between said two rows of flues, said massive wall being devoid of openings, extending the full height of the cell-defining wall and of a thickness at least four times the thickness of the said heat-transmitting wall; a row of regenerators in the lower portion of each cell directly beneath the coking chamber in said cell and comprising two exterior regenerators communicating, respectively, with the four exterior groups of heating flues on opposite sides of the coking chamber thereabove, and a regenerator communicating with the four interior groups of flues on opposite sides of the coking chamber thereabove, said first-named regenerators being operable for flow in one direction and said last-named regenerator being simultaneously operable for flow in the opposite direction, said regenerators communicating directly with the bases of said vertical flues for supplying air to said flues to support combustion of rich fuel gas fed directly to said flues and the row of regenerators in each cell communicating only with the heating flues on opposite sides of the coking chamber in said cell, whereby the supply of heated air to the heating flues of each coking chamber and the withdrawal of the products of combustion from these heating flues is independent of the supply of heated air to and the withdrawal of the products of combustion from the heating flues of other coking chambers of the battery thus permitting regulation of the heating of each coking chamber independently of the other coking chambers of the battery.

5. A coke oven battery comprising, in combination, a plurality of horizontally-elongated cell-defining walls disposed in spaced relationship defining horizontally-elongated cells spaced from each other so that the median of each cell is spaced from the median of a contiguous cell a distance of from 4½ to 5 feet; a horizontally-elongated coking chamber in the upper portion of each cell; each cell-defining wall comprising a heat-transmitting wall on each side thereof defining a side wall of each of the two coking chambers on opposite sides of said cell-defining wall, two rows of vertical flues, one row being positioned at one side and the other row on the other side of the upper portion of said cell-defining wall, each row of flues comprising two exterior and two interior groups of flues, channels connecting the tops of the exterior groups, respectively, with the tops of the interior groups, the two exterior groups being simultaneously operable for flow in one direction and the two interior groups being simultaneously operable for flow in the opposite direction, and a massive refractory wall extending crosswise of the battery between said two rows of flues, said massive wall being devoid of openings, extending the full height of the cell-defining wall and of a thickness at least four times the thickness of the said heat-transmitting wall; a row of regenerators in the lower portion of each cell directly beneath the coking chamber in said cell and comprising two exterior regenerators communicating, respectively, with the four exterior groups of heating flues on opposite sides of the coking chamber thereabove, and a regenerator communicating with the four interior groups of flues on opposite sides of the coking chamber thereabove, said first-named regenerators being operable for flow in one direction and said last-named regenerator being simultaneously operable for flow in the opposite direction, said regenerators communicating directly with the bases of said vertical flues for supplying air to said flues to support combustion of rich fuel gas fed directly to said flues and the row of regenerators in each cell communicating only with the heating flues on opposite sides of the coking chamber in said cell, whereby the supply of heated air to the heating flues of each coking chamber and the withdrawal of the products of combustion from these heating flues is independent of the supply of heated air to and the withdrawal of the products of combustion from the heating flues of other coking chambers of the battery thus permitting regulation of the heating of each coking chamber independently of the other coking chambers of the battery.

rior groups being simultaneously operable for flow in the opposite direction, and a massive refractory wall extending crosswise of the battery between said two rows of flues, said massive wall being devoid of openings, extending the full height of the cell-defining wall, from 14½ to 28½ inches thick and of a thickness at least four times the thickness of the said heat-transmitting wall; a row of regenerators in the lower portion of each cell directly beneath the coking chamber in said cell comprising two exterior regenerators communicating, respectively, with the four exterior groups of heating flues on opposite sides of the coking chamber thereabove, and an interior regenerator communicating with the four interior groups of flues on opposite sides of the coking chamber thereabove, said exterior regenerators being operable for flow in one direction and said interior regenerator being simultaneously operable for flow in the opposite direction, said regenerators communicating directly with the bases of said vertical flues for supplying air to said flues to support combustion of rich fuel gas fed directly to said flues and the row of regenerators in each cell communicating only with the heating flues on opposite sides of the coking chamber in said cell, whereby the supply of heated air to the heating flues of each coking chamber and the withdrawal of the products of combustion from these heating flues is independent of the supply of heated air to and the withdrawal of
